(57) **CLAIM**

The ornamental design for a charging cradle, as shown and described.

DESCRIPTION

FIG. 1 is a perspective view of the charging cradle according to the present design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 illustrates a perspective view, in which a foldable smartphone is being supported by the charging cradle.

In the drawings, the broken lines illustrate portions of the charging cradle that form no part of the claimed design.

1 Claim, 5 Drawing Sheets
